MATRIX GRINDING AND MARKING
MACHINE

John E. Sheaffer, Louisville, Ky.

Application April 14, 1937, Serial No. 136,943

7 Claims. (Cl. 51—110)

This invention relates to machines especially adapted for reconditioning matrices and marking the latter for identification so that they may be readily distinguished from other matrices which have not been reconditioned.

The primary object of the invention is the provision of a device of the above stated character for reconditioning matrices by grinding the outside walls of said matrices to remove therefrom 10 crevices which fill with metal when molten metal is shot into the matrices and produce hairlines rendering reading matter with a fuzzy appearance.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a top plan view illustrating a machine for reconditioning and marking matrices and constructed in accordance with my invention.

Figure 2 is a vertical sectional view illustrating the same.

Figure 3 is a bottom plan view partly broken away to show the ejector and stamping mechanisms.

Figure 4 is a plan view showing the grinding mechanism having the head of the machine removed.

Figure 5 is a sectional view taken on the line 5—5 of Figure 2.

Figure 6 is a sectional view taken on the line 6—6 of Figure 2.

Figure 7 is a sectional view taken on the line 7—7 of Figure 6.

Figure 8 is a sectional view taken on the line 8—8 of Figure 1.

Figure 9 is a fragmentary sectional view taken on the line 9—9 of Figure 2.

Figure 10 is a fragmentary sectional view showing a portion of the grinding element and a part of the track with the matrix presser therein.

Referring in detail to the drawings, the numeral 1 indicates a base on which is mounted a casing 2 including removable sections indicated by the character 3 to give access to the interior of the casing. The upper end of the casing is closed by a removable head 4 and secured in the casing is a bracket 5 cooperating with the base 1 in supporting a vertically arranged post 6 on which is journaled a hub 7, a portion of which is externally screw threaded and a portion is shaped to

provide a ratchet gear 8. A worm gear 9 is secured on the hub 7 and also located on the latter is a cam supporting plate 10 engaging one side of the worm gear. A spacing collar 11 is threaded on the hub 7 into engagement with the other side of the worm gear. Supported by the plate 10 and journaled on the hub is a cam 12 of a selected shape. A spring pressed dog 13 is pivoted on the cam and normally engages with the ratchet gear to establish a drive between the hub 10 and the cam. A release mechanism 14 is journaled on the head 4 and may be positioned to engage with the dog 13 to disengage the latter from the ratchet gear to establish a drive between the hub 7 and the cam. The release mechanism 14 is capable of being rotated in two directions, one in engagement with the dog to hold the latter disengaged from the ratchet gear and the other into a position to free the dog to reestablish the drive between the hub 7 and the cam. The release mechanism 14 when positioned to disengage the dog 13 from the ratchet gear 8 moves said dog into engagement with a stop 15 on the cam.

The release mechanism 14 has spaced notches 14' to be engaged by a spring pressed dog 15' for releasably holding the release mechanism in either of its positions.

Supported by the base and detachably secured to the latter is an electric motor 16, the shaft of which is geared to a shaft 17, the latter being suitably mounted in the casing 2 for rotation. A worm 18 is secured on the shaft 17 and meshes with the worm gear 9. The shaft of the motor 16 also has secured thereto a circular grinding element 19. The electrical feed conductors for the electric motor 16 are indicated by the character 20 and may be connected in any well known manner to an electrical output and include or have connected therein a control switch 21 operable from the exterior of the casing.

The head 4 is provided with a chamber 22 in which operates the grinding element 19, an ejector mechanism and a stamping mechanism. The ejector mechanism and stamping mechanism will be hereinafter described in detail. The head 4 has a slot communicating with the chamber 22 in which is mounted a housing 23 including a magazine or hopper 24 and a track or guide 25. Matrices are stacked in the magazine 24 and are ejected therefrom one at a time onto the track which guides said matrices into engagement with the grinding element 19 and past said grinding element into a chute 26 forming a part of the housing 23. The chute 26 includes inclined 55

guides or tracks 27 connecting one end with one end of the guide or track 25 and the other end of said guide or track 27 terminates above a receiving tray or box. A spring actuated presser 29 operates in the housing 23 and cooperates with the track 25 in slidably supporting the matrices and to urge one at a time into engagement with the grinding element 19. A portion of the track 25 under the presser 29 is cutaway so that a face of a matrix will be brought into engagement with the grinding element 19. The presser 29 is of sectional formation with the sections loosely connected.

An ejector 30 is slidably supported in the housing 23 for the purpose of ejecting the lowermost matrix of the stack of matrices located in the magazine 24 into the guide or track 25. The ejector has a finger piece 31 operating in a slot 32 formed in the housing 23 and also secured to the ejector is a post 33 carrying a roller 34 which rides on the cam 12. A lever 35 is pivoted on the head 4 and one end has connected thereto a coil spring 36 and the other end has pivoted thereto a link 37 and the latter is pivotally connected on the ejector. The spring 36 acts to drive the ejector when permitted by the cam. The cam acts to retract the ejector against the action of the spring 36, that is, the high face of the cam retracts the ejector and as the roller 34 of the post 33 passes off of the high face of the cam the spring 36 drives the ejector to force the lowermost matrix into the track or guide 25. It is to be understood that when the ejector is moved into a retracted position it moves from under the lowermost matrix in the magazine to become engaged with one end of said lowermost matrices so that the latter will be shoved into the track or guide 25 when the cam releases the ejector. It takes one complete revolution of the cam to 40 retract the ejector and to release the latter for shoving the lowermost matrix in the magazine into the track or guide 25. The matrix when moved into the track or guide 25 by the ejector clears itself from the remaining matrices so that 45 the next matrix comes to rest upon the ejector and as the latter moves into a retracted position said last-named matrix then becomes engaged at one end with the ejector. The ejector on its next operation forces the latter-named matrix 50 into the track or guide 25 causing the first ejected matrix to progress along the track or guide. This operation continues as long as the machine is in operation and the magazine contains matrices. As the matrices advance along the track or guide 25 one at a time comes in contact with the grinding element 19 to have the outside walls thereof dressed to remove imperfections. As the matrices are dressed they pass 55 into the chute 26 and thence into the tray 28 and arranged in the latter in a stacked formation and each disposed vertically. This is accomplished by a mechanism which will be herein-after more fully described in detail. The magazine 24 is of a size to accommodate the matrices of a font and also three or more duds shaped similar to a matrix. The purpose of the duds is to bring about the complete feeding of all of the matrices through the machine into the tray 28 60 and as the last matrix reaches the tray 28 the duds are then within the machine or the track 25 thereof and will be forced therefrom by the next run or batch of matrices acted on by the machine. The operation of the ejector with the 65 electric motor 16 running can be stopped and

started through the manipulation of the control mechanism 14.

The magazine 24 has a slidable gate 38 which may be adjusted relative to the track 25 and cooperates therewith in permitting only one matrix to be ejected by the ejector from the magazine onto the track at a time. The gate 38 being adjustable vertically is for the purpose of varying the size of the space between itself and the track to accommodate matrices of different thicknesses. The gate is adjusted vertically in either direction by a hand operating means 39 and the upper end of the gate is provided with a shoulder 40 cooperating with a flange 41 on the magazine to form a gage. The use of the gage is for the purpose of bringing about the adjustment of the gate to form a space between itself and the track of a size in accordance with the thickness of a particular or selected matrix. By positioning a selected matrix on the flange 41 and bringing the shoulder 40 in engagement therewith will bring about an adjustment of the gate relative to the track to form a space only large enough to permit the selected matrix to pass from the magazine into the track by the ejector and one 25 at a time.

A marker 42 is slidably supported by the guide or track 25 directly under the magazine and is connected to a slidable head 43 carried by the head 4. A plate 44 is connected to the head 43 and one end thereof is pivoted to the head 4, as shown at 45. The plate 44 has a slot 46 through which extends a pin 47 carried by the head 4 for limiting the pivotal movement of the plate. A coil spring 48 is connected to the plate 44 and to the head 4 and acts to retract the marker 42 out of the path of a matrix in the guide or track 25. An arm 49 is secured on the plate 44 and is engaged by a cam 52' secured on the cam 12 and is also engaged by a pivotally mounted lever 50 one end of which has connected thereto a coil spring 51 and the other end is provided with an adjustable pin 52 engageable with the head 4 and acts to limit the movement of the lever 50 under the action of the spring 51. The spring 51 acts to drive the plate 44 in a direction to force the marker 42 to travel in a direction for marking the lowermost matrix in the magazine 24. As the arm 49 rides off of the cam 52', the lever 50 is swung on its pivot with considerable force by the spring 51. The swinging movement of the lever is checked by the pin 52 engaging the head 4. The lever 50 being in engagement with the arm 49 when the latter disengages the cam 52' swings the plate 44 on its pivot 45 with considerable force carrying therewith the head 43 and the marker 42. The plate 44 may continue to travel under its momentum after the checking of the swinging movement of the lever 50. The marker 42 engages with the matrix during the time that the plate 44 is swinging under its momentum so that the marker will receive a hammer-like blow which is sufficient to bring about marking of the matrix. A stop 54 is secured on the plate 44 and may be engaged by a control mechanism 55 carried by the head when it is desired to hold the marker 42 in a retracted or inoperative position.

It is to be understood that the control mechanism 55 is operable from the exterior of the head 70 so that the marking mechanism can be rendered operative and inoperative when desired. The purpose of marking the matrices is so that they can be identified after being reconditioned from matrices which have not been reconditioned. 75

The box or tray is slidably supported, as shown at 56', and is adapted to receive the matrices as they are reconditioned, they being stacked therein and each disposed vertically. Located just 5 above the tray 28 are spring fingers 57' adapted to engage the matrices as they enter the tray. A follower 58 operates in the tray with a sliding movement and is connected with a slidably mounted plunger 59 on which is journaled a roller 60. The roller 60 rides the cam 12 for the purpose of reciprocating the follower 58. Each time a matrix is received in the tray the follower 58 is reciprocated for the purpose of advancing the tray endwise permitting the matrices to stack 15 in the tray one behind the other with the follower and fingers 57' cooperating in maintaining the matrices in stacked position. Each time the cam 12 completes one revolution a matrix is deposited in the tray and consequently the follower 20 58 is reciprocated once on each revolution of the cam 12 to bring about an advancement of the tray in an endwise direction to provide a space for the reception of the following matrix. As the tray 28 is advanced on the stacking of matrices 25 therein some of the matrices stacked within the tray will become disengaged from the fingers 57' however they will maintain their vertical positions by the upright walls of the tray and the matrices stacking therebehind and still in engagement with the fingers 57'. The tray 28 can be easily removed from its support after completing a run or reconditioning of a group of matrices so that the matrices reconditioned can be easily emptied or removed from the tray. The 30 plunger 59 is spring pressed to maintain the roller 60 thereof in contact with the periphery of the cam 12. The follower 58 includes the slidably supported head 61 to which is secured a plunger 62 of the spring pressed type and secured to the 35 plunger 59 is an arm 63 having contact with the plunger 62 so that when the plunger 59 is moved by the cam to advance the follower 58 a drive is established by the arm 63 from the plunger 59 to the plunger 62. One end of the tray is fully open 40 so that said end may ride past the head 61 of the follower when the tray is removed or replaced in 45 position on the machine.

The housing 23 has formed therein an air passage 63', one end of which is connected to a 50 valve 64 located exteriorly of the head and the other end is connected to a nozzle 65. The valve 64 may be connected to an air supply (not shown) by a pipe 66. The nozzle 65 is for the purpose of directing air under pressure across the face of 55 the grinding element to remove from the grinding element grindings. As the grindings are blown from the grinding element they pass through a port 67 in the head 4 and into a collecting bag 68. The air is turned on by opening the valve 60 64 and may be cut off at any time desired by closing the valve.

Linotype machines and other line casting machines employ matrices of different thicknesses, however, the matrices of the same thickness are 65 segregated and kept in fonts and after they have been in use for a period of time the outer walls become damaged or have crevices formed therein and these crevices become filled with metal when the matrices are shot with molten metal and 70 which creates hairlines. Heretofore, matrices becoming so damaged or worn have been discarded and in order that matrices damaged in the manner described may be reconditioned and rendered fit for further use my machine as shown in 75 this application and heretofore described in de-

tail is employed. To recondition matrices of a certain size one of the matrices is placed between the shoulder 40 of the gate 38 and the flange 41 and the shoulder brought into engagement with the matrix, thereby properly adjusting the gate 5 so that matrices of this size or thickness will be fed one at a time from the magazine into the track 25 by the ejector mechanism. After the setting of the gate the matrices are stacked in superimposed relation in the magazine 24. The 10 motor 16 is then started, the control mechanism 14 first being positioned to render the ejector mechanism inoperative. After the motor has obtained its full momentum the control 14 is actuated to connect the cam 12 to the drive between 15 the latter and the motor. The cam 12 being in operation first operates the marking mechanism to mark the lowermost matrix in the tray and at the same time the cam retracts the ejector. After 20 the marking of the matrix the cam releases the 25 ejector which acts to shove the lowermost matrix just marked into the track or guide 25. This same operation continues consequently advancing the matrices along the track and as each matrix arrives at a certain place on the track a face 30 thereof comes in contact with the grinding element so that one of the outer walls is ground to remove crevices therefrom. The matrices being advanced in a step by step movement will, after 35 a certain amount of grinding, move onto the inclined guide 27 and pass therefrom into the tray 40 28. The matrices being stacked on end in the tray 28 as they are received therein and as each matrix enters the tray the latter is advanced endwise to provide a space for the following matrix. When first assembling the matrices in the magazine 24 a plurality of duds are added to the stack 45 so that said duds in passing through the machine will exhaust from the machine into the tray all of the matrices which have been stacked in the rack. After the passing and reconditioning of one side wall of all of the matrices they are removed from the tray 28 and turned over and repositioned in the magazine 24. At this time the marking mechanism is rendered inoperative by 50 manipulating the control 55 so that said matrices will be again passed through the machine in a step by step movement by the ejector receiving necessary additional grinding on both walls to remove crevices and defects therefrom so that the 55 matrices when again received in the tray will have been first marked for identification and then reconditioned, that is, both outer walls reconditioned by having crevices removed therefrom rendering said matrices in proper condition for further successful use.

What is claimed is:

1. A machine for reconditioning matrices comprising a supporting structure, a track carried by said structure and including a magazine for receiving matrices to be fed one at a time onto said track, an ejector mechanism for ejecting matrices one at a time from said magazine onto said track and to advance said matrices in a step by step movement along the track, a power means carried by the supporting structure, a marking mechanism carried by said supporting structure for marking the matrices one at a time carried by said magazine and prior to being advanced from the magazine onto the track by said ejector mechanism, and a drive means driven by said power means for operating the ejector mechanism and the marking mechanism, a grinding mechanism operated by said power means to act 75

on said matrices as advanced into a certain position onto the track by the ejector mechanism.

2. A machine for reconditioning matrices comprising a supporting structure, a track carried by said structure and including a magazine for receiving matrices to be fed one at a time onto said track, an ejector mechanism for ejecting matrices one at a time from said magazine onto said track and to advance said matrices in a step by step movement along the track, a power means carried by the supporting structure, a marking mechanism carried by said supporting structure for marking the matrices one at a time carried by said magazine and prior to being advanced from the magazine onto the track by said ejector mechanism, a drive means driven by said power means for operating the ejector mechanism and the marking mechanism, a grinding mechanism operated by said power means to act on said matrices as advanced into a certain position on the track by the ejector mechanism, and means receiving the matrices after being marked and acted upon by the grinding mechanism and to arrange them in stacked formation.

3. A machine for reconditioning matrices comprising a supporting structure, a track carried by said structure and including a magazine for receiving matrices to be fed one at a time onto said track, an ejector mechanism for ejecting matrices one at a time from said magazine onto said track and to advance said matrices in a step by step movement along the track, a power means carried by the supporting structure, a marking mechanism carried by said supporting structure for marking the matrices one at a time carried by said magazine and prior to being advanced from the magazine onto the track by said ejector mechanism, a drive means driven by said power means for operating the ejector mechanism and the marking mechanism, a grinding mechanism operated by said power means to act on said matrices as advanced into a certain position on the track by the ejector mechanism, means receiving the matrices after being marked and acted upon by the grinding mechanism and to arrange them in stacked formation, and pneumatic means for removing grindings from the grinding mechanism.

4. A machine for reconditioning matrices comprising a supporting structure, power means carried by said structure, a grinding mechanism driven by said power source, a track carried by said structure for guiding matrices into and out of engagement with the grinding mechanism, a magazine for delivering onto said track matrices, an ejector for ejecting matrices one at a time from said magazine onto said track and to advance the matrices in a step by step movement along said track, spring means acting to operate the ejector in one direction, a cam connected to said ejector and working to move the ejector in an opposite direction and for releasing the latter to be actuated by said spring means, a post carried by said supporting structure and forming a journal for said cam, a worm gear journaled on said post, a worm meshing with the worm gear, a shaft journaled on the supporting structure and having the worm secured thereto, means connecting the shaft to said power

means, a manually controlled means for connecting and disconnecting the cam to said worm gear, a tray slidably mounted on the supporting structure to receive the matrices as advanced from the track, and a follower operated by said cam to advance the tray endwise and stack the matrices therein.

5. A machine for reconditioning matrices comprising a supporting structure, a power means carried by said structure, a grinding mechanism driven by said power means, a track carried by said supporting structure to guide matrices into and out of engagement with the grinding mechanism, a magazine carried by the supporting structure for delivering matrices onto said track, an ejector mechanism operated by said power means for ejecting matrices one at a time from the magazine onto said track and to advance the matrices in a step by step movement along said track, a marker carried by said track for marking a matrix after it has been advanced from the magazine onto said track, and means driven by said power source for operating the marker.

6. A machine for reconditioning matrices comprising a supporting structure, power means carried by said structure, a grinding mechanism driven by said power means, a track carried by said supporting structure to guide matrices into and out of engagement with the grinding mechanism, a magazine carried by the supporting structure for delivering matrices onto said track, an ejector mechanism operated by said power means for ejecting matrices one at a time from the magazine onto said track and to advance the matrices in a step by step movement along said track, a marker carried by said track for marking a matrix after it has been advanced from the magazine onto said track, a drive means intermittently operated and driven by said power means to operate the marker with hammer-like blows.

7. A machine for reconditioning matrices comprising a supporting structure, a power means carried by said structure, a grinding mechanism driven by said power means for acting on a matrix supported by a certain portion of said track, a magazine for supporting the matrices and delivering them onto said track, an ejector for ejecting matrices one at a time from the magazine onto said track and to advance the matrices in a step by step movement over said track, a cam for operating the ejector, spring means acting on the ejector to maintain the latter in engagement with the cam, a drive means between the power means and the cam, a slideable marker for marking the matrices as they move onto the track from said magazine and including a slidably supported head, a plate connected to said head and pivotally mounted on said supporting structure, a spring acting on said plate, an arm secured to said plate, a lever pivotally mounted on the supporting structure and engaging the arm and including a stop means for limiting its pivotal movement in one direction, a spring acting on said lever, and a cam carried by the first cam to engage and disengage with said arm for imparting movement to said plate which in turn actuates the marker with a hammer-like blow.
